[57] CLAIM

The ornamental design for a candle or similar article, substantially as shown and described.

DESCRIPTION

FIG. 1 is a front perspective view of a candle showing my new design, the back of the candle being identical to the front of the candle.

FIG. 2 is a top perspective view thereof.

FIG. 3 is a front perspective view of a candle showing a modified form of my new design, the candle being symmetrical about its axis.

FIG. 4 is a top plan view thereof.
